UNITED STATES PATENT OFFICE.

JOHN H. LARRABEE, OF WASHINGTON, DISTRICT OF COLUMBIA.

COMPENSATING APPARATUS FOR PANTOGRAPHS.

Application filed November 3, 1924. Serial No. 747,617.

My invention relates to a compensating device for use with any pantograph and has for an object the reproduction of charts, designs, drawings or diagrams with great accuracy.

Another object of my invention is to provide a device that will give a true reproduction even when the chart or other work to be copied, is distorted.

10 A further object is to provide a means for increasing the efficiency and reducing the cost of such work.

With these and other objects in view, my invention consists in the combination, construction and arrangement of parts as will be hereinafter fully described.

Reference is to be had to the accompanying drawings forming part of this specification in which like reference characters indicate corresponding parts throughout the several views, and in which Figure 1 is a plan view of my invention. Figure 2 is a cross section on the line 2-2 of Figure 1. Figure 3 is a cross section on the line 3-3 25 of Figure 1. Figure 4 is a cross section on the line 4-4 of Figure 1.

With particular reference to Figure 1 numerals 1, 2, 3 and 4 represent the arms of any pantograph as used in reproducing designs, drawings or diagrams. 5 is the anchor point, 6 the tracing point and 7 the reproducing point of the particular pantograph used to describe my invention. 8 is a copy board upon which the work to be reproduced is secured. Copy board 8 is mounted on bearings 9 (Fig. 4) which are preferably of the ball type, and slide on the surface of the metal bed 10. In this particular embodiment of my invention, the movement of copy board 8 is confined to one direction by means 40 of rail 11, which is rigidly attached to the metal bed 10, and bearings 12 rigidly attached to the under side of the copy board 8 and sliding on the respective sides of rail 11.

45 An arm 13 is pivoted to arm 1 at 15. An arm 14 is pivoted to arm 3 at 16. Arms 13, 14 and the compensating bar 18 are pivoted together at point 17. The arms 13 and 14 are so proportioned and located in relation to 50 arms 1 and 3 that they form an auxiliary pantograph with an anchor point in common with the anchor point 5 of the larger pantograph, thus providing for a movement of the point 17 in the same direction and 55 proportional to any movement of the tracing point 6.

As shown in Figure 3, the compensating bar is positioned between the slotted rails 19. Compensating bar 18 has a slot 20, preferably recessed, the axis of which extended passes through point 17. Passing through the slot 21 of rails 19 and through the slot 20 of compensating bar 18 is a pivot 22, the lower portion of which freely slides in the slot of the lower rail 19 and the upper portion of which is threaded to carry nut 23. By adjusting nut 23 the pivot 22 is made to rigidly engage the compensating bar 18 by means of the extended portion 24 of the pivot 22 and the sleeve 25 slidable about 65 pivot 22 and in the slot of upper rail 19. The rails 19 are rigidly supported by brackets 26 which in turn are securely fastened to the table 27. Slotted rails 19 are in a position parallel to the two opposite sides of 70 the copy board 8. Compensating bar 18 is joined to copy board 8 by an adjustable connecting rod 28. Rod 28 is movably connected to bar 18 at 29 and to copy board 8 at 30. The whole apparatus is preferably mounted 80 on a table 27.

The apparatus as above described operates in the following manner:

The sides of the copy board 8 are marked North, South, East and West for convenience in explanation. A copper plate 31 or other medium upon which the reproduction is to be pantographed is placed under the reproducing point 7. It will be readily seen that for all movements of the tracing point 6, the 90 reproducing point 7 will move over the copper plate in the same direction and through distances proportional to the movements of the tracing point 6 in the ratio $\frac{5-7}{7-6}$.

Assume that there is placed on the copy board 8 a print of a chart having its North-South dimension correct and its East-West dimension shortened by shrinkage, and that it is desired to reduce this chart on the copper plate 31 and at the same time restore the true proportion between North-South and East-West dimensions. The pantograph can be set so that the reproducing point 7 will reproduce all movement of the tracing point 6 in a North-South direction on a desired scale but distances in an East-West direction traced by the tracing point 6 will then be reproduced in a different scale and shorter in proportion to the shrinkage 110 in the chart being traced.

If, however, when the tracing point 6 is

moving in an East-West direction the copy board can be made to move progressively under the tracing point in the same direction and in an amount equal to the shrinkage in the chart, then the reproducing point 7 will reproduce East-West distances traversed by the tracing point 6 in correct proportion to the true dimensions of the chart and the effect of shrinkage will be eliminated. The accomplishment of the required progressive movement of the copy board under the tracing point as the tracing point is moved in an East-West direction is a feature of my invention.

15 When the tracing point 6 is moved in a North-South direction the center of the joint 17 moves in a North-South direction and the pivot 22 slides in the slotted rail 19 in a North-South direction and there is 20 no East-West movement of the connecting rod 28. Hence the copy board 8 remains stationary.

When the tracing point 6 moves in an East-West direction the center of the joint 25 17 moves in an East-West direction, the compensating bar 18 pivots about point 22 and an East-West movement is communicated to the connecting rod 28 and thence to the copy board 8. This movement of the 30 copy board is proportional to the East-West movement of the tracing point 6 and in a ratio depending upon the distance of the pivot 22 from the connecting rod 28.

When the pivot point 22 is South of the 35 connecting rod the copy board 8 and tracing point 6 will move in the same direction thus compensating for shrinkage and when the pivot 22 is North of the connecting rod 28 the copy board 8 and the tracing point 40 6 will move in opposite directions thus compensating for expansion.

When the pivot point 22 is on a line with the connecting rod 28 the copy board 8 will 45 remain stationary for all movements of the tracing point 6. This is the position of pivot point 22 for use when no distortion is to be compensated.

In operating the pantograph with my 50 compensating device, the amount of shrinkage or expansion to be compensated for must be determined and the pivot point 22 set accordingly. Settings of the pivot point 22 necessary to produce various percentages of compensation may be computed and graduated on the compensating bar in any convenient scale.

It will be understood that the above description and accompanying drawings com-

prehend only the general and preferred embodiment of my invention and that various 60 minor changes in details of construction, proportion, and arrangement of parts may be made within the scope of the appended claims and without sacrificing any of the 65 advantages of my invention.

Having described my invention, what I claim is:

1. A parallelogram type pantograph 70 copying arrangement comprising interconnected arms, a tracing point and a reproducing point located on said arms, a movable copy-board and means connecting the interconnected arms and copy-board for imparting a progressive movement to the copy-board in response to movement of the tracing point thereover.

2. A parallelogram type pantograph 75 copying arrangement comprising pairs of interconnected arms, an anchor stem, one pair being pivoted to the anchor stem and another pair carrying a tracing point and a reproducing point, a movable copy-board and means including an auxiliary pantograph attached to said stem and said first named arms for imparting a progressive movement to the copy-board in response to movement of the tracing point thereover.

3. A parallelogram type pantograph 80 copying arrangement comprising pairs of interconnected arms, an anchor stem, one pair being pivoted to the anchor stem and another pair carrying a tracing point and a reproducing point, an auxiliary pantograph attached to said stem and said first named arms, a movable copy-board and means connected between the auxiliary pantograph and copy-board whereby a progressive movement is imparted to the latter in response to movement of the tracing point 85 thereover said means including interconnected members, one of which is pivotally mounted.

4. A parallelogram type pantograph 90 copying arrangement comprising interconnected arms, a tracing point carried by one of said arms, a reproducing point movable with the tracing point positioned on another of said arms, a movable copy-board over which the tracing point is operable, and means connected to the interconnected arms and copy-board for moving the latter to compensate in the reproduced copy for dimensional variations in the copy to be traced.

JOHN H. LARRABEE.
